ELASTIC FASTENER FOR HAIR OR THE LIKE

Herman W. Patterson, Overland Park, Kans.

Application November 13, 1957, Serial No. 48,445

Term of patent 14 years

(Cl. D86—10)

Fig. 1 is an elevational face view of an elastic fastener for hair or the like, showing my design, and
Fig. 2 is an edge view thereof.

I claim:

The ornamental design for an elastic fastener for hair or the like, as shown.
